ORNAMENT FOR SPECTACLE FRAME PARTS

Vito Errico, New Hyde Park, and Harry Berman and Dominick Lofrese, Bronx, N. Y., assignors to Victory Optical Manufacturing Co., Newark, N. J., a corporation of New Jersey

Application March 25, 1952, Serial No. 19,047

Term of patent 14 years

(Cl. D57—1)

To all whom it may concern:

Be it known that we, Vito Errico, Harry Berman, and Dominick Lofrese, citizens of the United States, residing at 125 Rhodes Drive, New Hyde Park, New York, 1533 Townsend Avenue, Bronx, New York, and 2326 Fish Avenue, Bronx, New York, respectively, have invented a new, original, and ornamental Design for an Ornament for Spectacle Frame Parts, of which the following is a specification, reference being had to the accompanying drawing, forming part thereof.

Fig. 1 is a front elevational view of an ornament for spectacle frame parts, showing our novel design.

Fig. 2 is a top plan view of that shown in Fig. 1.

The dotted line showing of a spectacle frame part in Figs. 1 and 2 is for illustrative purposes only.

We claim:

The ornamental design for an ornament for spectacle frame parts, substantially as shown and described.

VITO ERRICO.
HARRY BERMAN.
DOMINICK LOFRESE.
